UNITED STATES PATENT OFFICE

159,278

TIME REMINDER

Warren B. Leland, Spokane, Wash.

Application October 29, 1949, Serial No. 5,771

Term of patent 14 years

(Cl. D42—8)

To all whom it may concern:

Be it known that I, Warren B. Leland, a citizen of the United States, residing at Spokane, in Spokane County, and State of Washington, have invented a new, original, and ornamental Design for Time Reminder, of which the following is a specification, reference being had to the accompanying drawing, forming a part thereof.

Fig. 1 is a front perspective view of the time reminder, showing my new design. The chain element shown in Fig. 1 has been omitted from Figs. 2 and 3 for convenience of illustration.

Fig. 2 is a rear elevational view of the same; and

Fig. 3 is a sectional view taken on line 3—3 of Figure 2.

I claim:

The ornamental design for a time reminder, as shown and described.

WARREN B. LELAND.
